UNITED STATES PATENT OFFICE

GEORGE H. HART, OF WEST HARTFORD, CONNECTICUT.

ELECTRIC SWITCH.

1,180,493.

Specification of Letters Patent. Patented Apr. 25, 1916.

Application filed July 27, 1915. Serial No. 42,176.

To all whom it may concern:

Be it known that I, GEORGE H. HART, a citizen of the United States, residing at West Hartford, county of Hartford, State of Connecticut, have invented a certain new and useful Improvement in Electric Switches, of which the following is a full, clear, and exact description.

My invention relates to electric switches and has for its object to produce a simple and compact electric switch in which a spring-pressed ball acts upon a member carrying a cam to produce the desired snap movement, both members oscillating about a common axis.

The following is a description of an embodiment of my invention, reference being had to the accompanying drawings, in which,

Figure 1 shows a side elevation of the switch mechanism mounted on a suitable base; Fig. 2 is a section of the same on the line 2—2, Fig. 1; Fig. 3 is an enlarged detail showing parts in section with the switch arm in one position; and Fig. 4 is an enlarged detail of the switch arm in the other position.

Referring more particularly to the drawings, 1 is the switch base of a two push button switch, on which is supported a pivot 2. On this pivot 2 is an elongated member 3 having in each end an elongated chamber, each chamber containing a ball 4 acted upon by a spring 5. The elongated member 3 has its walls slotted and in the slots 6 thus formed is located a flat switch arm 7 journaled upon the pivot 2 and provided with cams 8 having oppositely extending high points 9. Extending in one direction from the cams 8 is a projection 10, which when the switch arm is in either of its extreme positions, is engaged by one of the balls 4 acting as an abutment to assist in defining the position of the switch arm at the end of each throw. The switch arm also carries contacts 11 electrically connected together but insulated from the arm proper and adapted to engage and disengage contacts 12—12' carried by the base and constituting circuit terminals. The base also carries stops 13—13' which are engaged by the lower end of the switch arm so as to also limit movements. Pivoted to the actuating member 3 are push buttons 14—14' guided by the plate 15. These push buttons are pivoted to the actuating member by

pivots, the plane of whose axes is substantially in line with the axis of the chambers within the actuating member, the axes of the pivots intersecting the axis of the chambers and being at right angles thereto.

In actuating the switch with the parts in the position shown in Fig. 1, the push button 14 is depressed, whereupon the actuating member 3 is turned until the balls 4 pass the high points 9 of the cams 8, whereupon the springs 5 force the balls inward against sloping surfaces of the cams, causing the switch arm to snap clockwise so as to open the switch. When the switch is opened the depression of the push button 14 moves the switch arm in the opposite direction in a similar manner.

As will be evident to those skilled in the art, my invention permits of various modifications without departing from the spirit thereof or the scope of the appended claims.

What I claim is:

1. In an electric switch, the combination of an oscillating actuating member pivotally mounted at its central portion, a switch arm member pivotally mounted on the same axis as said actuating member, said switch arm member having two cams with oppositely projecting high points and said actuating member having two elongated chambers in line with said cams, two movable elements engaging said cams respectively, two springs tending to move said elements, each of said chambers containing one of said elements and one of said springs, and means for oscillating said actuating member.

2. In an electric switch, the combination of an oscillating actuating member pivotally mounted at its central portion, a switch arm member pivotally mounted on the same axis as the actuating member, said switch arm member having a cam with a central high point, and said actuating member having an elongated chamber whose axis is in line with said cam, a movable element engaging said cam, and a spring tending to move said element and hold it in engagement with said cam, said element and spring being within said elongated chamber, and means for oscillating said actuating member.

3. In an electric switch, the combination of an oscillating actuating member, pivotally mounted at its central portion, a switch arm member pivotally mounted on the same axis as the actuating member, one of said members having a cam with a central high

point and the other having an elongated chamber whose axis is in line with said cam, a movable cam-engaging element, and a spring tending to move said element and hold it in engagement with said cam, said engaging element and spring being within said chamber, and means for oscillating said actuating member.

4. In an electric switch, the combination of an oscillating actuating member pivotally mounted at its central portion, a switch arm member pivotally mounted on the same axis as the actuating member, said switch arm member having a cam with a

central high point, and said actuating member having an elongated chamber whose axis is in line with said cam, a movable element engaging said cam, and a spring tending to move said element and hold it in engagement with said cam, said element and spring being within said elongated chamber, and means for oscillating said actuating member consisting of two push buttons pivotally connected to said actuating member about axes which substantially intersect the axis of said chamber. 15 20 25

GEORGE H. HART.
